UNITED STATES PATENT OFFICE.

JOHN SACKER, OF FINSBURY PARK, LONDON, ENGLAND.

HAIR COMB.

1,426,111.

Specification of Letters Patent. Patented Aug. 15, 1922.

Application filed September 18, 1920. Serial No. 409,872.

To all whom it may concern:

Be it known that I, JOHN SACKER, a citizen of Russia, residing at 13 Blackstock Road, Finsbury Park, London, England, 5 have invented an Improved Hair Comb, of which the following is a specification.

My invention relates to a novel construction of comb particularly suitable for removing nits from the hair of persons' heads, 10 and from the hair of animals, such as dogs.

Combs for this purpose are usually made of flexible material such as celluloid, bone and the like and possess the disadvantage that when in use the teeth yield and allow 15 the nits to pass between them.

The object of my invention is to overcome this disadvantage and to this end I construct a comb of a practically rigid or non-flexible material such as metal with very fine 20 divisions between the teeth and as it is difficult to manufacture such a comb on account of the close spacing of the teeth I form the latter separate and secure them together or to a back or handle.

25 In a suitable arrangement for carrying out the invention each tooth is provided with holes for the reception of pins or bolts for securing the teeth together or in a back or handle. By this means the teeth can be very 30 easily detached and separately freed from accumulated dirt, thoroughly cleansed, and then re-assembled in the back or handle ready for use.

Instead of employing strips reduced in 35 thickness at the tooth end I may make use of strips of the same thickness throughout their length and assemble them with distance pieces or washers alternately between them, these distance pieces then providing the nec- 40 essary spacing between the teeth.

In a further modification I make use of strips formed with teeth at either end, the so-called backs being then provided in the middle and being connected together in any 45 of the ways above described. By these means two combs of different mesh may be provided in one and the same appliance.

In a modified construction according to 50 the invention the strips of metal or other material forming the teeth are reduced in thickness at the tooth end as compared with what may be termed the back portion, so that, when the said strips are assembled to form the comb, the necessary space is left 55 between the teeth. The strips may be secured together by being clamped between

two end plates or strips by means of pins or bolts passed through holes in the back portions and the said plates; or the back portions may be soldered or welded together. 60

To enable the invention to be fully understood, I will describe it by reference to the accompanying drawing in which:

Figure 1 is a sectional elevation of one form of comb made according to the invention. 65

Figure 2 is a section on the line 2—2 Figure 1.

Figure 3 is an elevation of a portion of a comb illustrating a modification. 70

Figure 4 is an elevation illustrating a further modification, and

Figure 5 is a section on the line 5—5 Figure 4.

Referring first to the construction of comb 75 illustrated in Figures 1 and 2, *a* indicates the strips constituting the teeth and *b* the two end plates or strips. *c* indicates a pair of pins or bolts which are passed through holes formed in each of the strips *a* and the plates 80 *b*. The strips *a* and the end plates *b* are threaded upon the said pins or bolts *c* and, washers *d* are introduced between the adjacent strips on the respective bolts *c* the whole being then tightly clamped together 85 by means of the nuts *e*, engaging the screw-threaded projecting ends of the pins *c*. In practice, the washers *d* may be made slightly thicker than the washers *d*, so that, when the comb is assembled, the strips 90 may be closer together at the tooth than at the back end, *e* are screws engaging threads in the pins *c* to prevent the nuts *e* from becoming accidentally detached from the said pins. 95

Figure 3 shows the modification of the comb in which the individual strips *a* are reduced in thickness at the tooth end as compared with the back portion, the latter being advantageously thicker than the said tooth 100 end at the parts embracing the bolts *c*. This arrangement enables the washers *d* to be dispensed with.

In Figures 4 and 5 I have indicated a modification of the arrangement illustrated in Figure 3, in which modification the strips *a* are formed with back portions *f* which are soldered together and additionally secured in place by means of the transverse pins or rivets *g*. 105

In the drawings single combs only are shown, but double combs may be made by 110

forming the strips *a* with teeth at both ends and extending the end plates *b* to correspond therewith. This arrangement is illustrated by dotted lines at *h* Figures 1 and 2.

5 As will be understood, combs made according to the invention possess certain advantages, since the whole of the comb is composed of an easily cleansable and unbreakable material such as metal, and in 10 those forms in which the teeth are not soldered together the parts can be easily separated so as to render the cleansing operation thorough and efficient.

Claims:

15 1. A hair comb constructed of non-flexible material, comprising teeth, provided with thickened portions at their ends, to space said teeth apart, means for securing said upper ends together to form a handle, 20 said handle being of a greater area than the

portion comprising the teeth, to secure a firm grip by the hand of the user.

2. A hair comb constructed of non-flexible material, comprising teeth, the upper ends of which are thickened to space them apart when secured together, each of said teeth being provided with a plurality of apertures, one of said apertures being at the lower extremity of the thickened portion, and the other at the upper extremity of said thickened portion pins adapted to be passed through said apertures for securing said teeth together. 25 30

3. A hair comb as claimed in claim 2, in which the thickened portions at the upper ends of the teeth, form a handle which is substantially rectangular in shape, to permit a firm grip by the user. 35

JOHN SACKER.
